UNITED STATES PATENT OFFICE.

JULES CARPENTIER, OF PARIS, FRANCE.

INDUCTION-COIL FOR IGNITING EXPLOSION-MOTORS.

No. 800,625.

Specification of Letters Patent

Patented Oct. 3, 1905.

Application filed February 8, 1905. Serial No. 244,757.

To all whom it may concern:

Be it known that I, JULES CARPENTIER, a citizen of the Republic of France, residing in Paris, France, have invented certain new and useful Improvements in Induction-Coils for Igniting Explosion-Motors, of which the following is a specification.

This invention has for its object an arrangement serving to modify the action of the interrupters of induction-coils and to allow them to produce in these coils, in particular when they are employed for igniting explosion-motors, a single spark per contact with the distributor. The advantage which this condition presents is easily understood. In effect, the duration of the contact at the distributor, which is variable with the speed of the motor, is rather considerable at low speeds and then corresponds to the emission in a coil with ordinary interrupter of a series of sparks, the first of these sparks being sufficient for effecting the ignition of the mixture. The others are useless and cause an unnecessary expenditure of electricity. The possibility of only emitting one spark per contact at the distributor therefore admits the realization of a saving which is of importance when the source of electricity consists of batteries or accumulators. The invention in question only introduces into the construction of the coils an insignificant complication and reduces itself in principle to the use at the extremity of the core next the interrupter of a flat solenoid of thin wire. This solenoid when the distributor sends a current into the primary of the coil receives a shunt of this current and contributes to the magnetization of the core; but while under the influence of this magnetization and by the action of the known devices of the interrupter the primary current is suddenly broken the small shunt-current produced in the solenoid subsists and in maintaining a slight magnetization in the core retains the movable armature until the moment when by the cessation of the contact at the distributor the current is itself broken. The parts of the interrupter then return to their initial position and the apparatus is ready to recommence. In the succession of the phases that have been enumerated there will have been produced, as will be readily conceived, only a single induced current and a single spark, which is the result aimed at.

The action of the device, it will be seen, is based upon the permanence of a small shunt-current in the auxiliary solenoid during the

entire contact at the distributor. It should here be observed that this shunt-current is of such weak intensity as to correspond to a perfectly negligible expenditure. 60

Instead of utilizing the core of the coil for actuating the interrupter recourse is sometimes had to an auxiliary electromagnet. The invention is obviously also applicable in this case. It suffices to provide this electromagnet with two windings, one of thick wire, which is in series with the primary of the coil, and the other of thin wire, which is connected in shunt. The action of the interrupter is evidently the same as in the first arrangement. 65 70

The accompanying drawings show two applications of the system.

Figures 1 and 2 are respectively a longitudinal section of a simple induction-coil and an end view thereof, the wooden casing being in section in both the figures. Fig. 3 is a side view of a commutator. Fig. 4 is a diagram of the circuits in the coil. Fig. 5 is a vertical section, and Fig. 6 a plan, of a type of coil used with an engine having more cylinders than one. Fig. 7 is a diagram of the wiring of Figs. 5 and 6. Fig. 8 is a diagram illustrating a slight modification. 75 80 85

The induction-coil consists, essentially, of a primary winding *a*, of a secondary winding *b*, and of a bundle or bar of soft iron *c*. The whole is placed in a wood casing *d* and suitably insulated. At the upper part is arranged the auxiliary coil *e* of fine wire, connected in shunt to the primary current. The said coil surrounds the upper end of the soft-iron bar *c*, which projects from the induction-coil proper, and it is contained in a wooden plate *f*, constituting a cover. Upon the latter is fixed, by means of two screw-contacts *g g*, the improved movable vibrating interrupter *h*. This vibrating interrupter is furnished with a plate having aperiodic oscillations and is designed to be easily dismounted to regulate it or to replace it. It is composed chiefly of the additional plate *v*, having aperiodic oscillation, a spring-terminal *x*, and a contact-screw *n*. These different parts are mounted on a bridge *o*, of suitable metal, fastened immovably on the rectangular frame inclosing the induction coil or coils by means of two screws *g g*, which pass through the screws *p p'*, the latter being screwed into blocks *q q'*, on which the bridge *o* rests. The screws *g g* engage the respective terminals *j j*, connected to the extremities of the primary coil. The screws *g g* are engaged, respectively, in 90 95 100 105 110

- sockets *j*, connected to the ends of the primary winding. It is necessary here to describe an accessory device of this induction-coil, the utility of which is very appreciable.
5. It is a commutator so arranged as either to arrest the action of the coil or to cause the interrupter to act as trembler or to cause it to perform a single stroke. This commutator is constituted as follows: Upon a lateral wooden plate *k*, closing the casing containing the coil, are arranged two contact-tongues *l m*, secured by screws. Below the said tongues there is mounted upon a plate *n* a semicircular disk *o*, having its center at *p*. This disk carries a stud *q*, which is engaged in the notch of a projection *r* of a circular plate *s* with a rib *t* serving as handle. The plate *s* is engaged in a circular groove formed in the wood *d* of the casing and is covered by an external ring *u*. In seizing with the fingers the rib *t* the rotation of the plate *s* can be effected, whereby the semidisk *o* can be placed in one of the three positions shown on the diagram Fig. 4. On this diagram the same letters of reference designate the same parts of the coil which have been above described. In addition, *A* is the battery, *B* the distributor, *C* the screw-terminal of the battery, *D* that of the commutator, and *E* that of the igniter.
15. In the middle position the primary circuit is completely open, which corresponds to the condition of rest. In the right-hand position the disk *o* is only in contact with the left-hand tongue *l*. The current of the battery therefore only passes through the primary circuit and the vibrating interrupter operates, but can give several sparks per stroke, because the shunt-circuit of the auxiliary coil *e* is open.
20. In the left-hand position the disk *o* is in contact with both the tongues *l m*. The battery-current then passes into the primary circuit *a* of the coil and into the shunt-circuit of the auxiliary coil *e*. The tongue *v* is then not only attracted by the core of soft iron *c* and breaks the primary circuit in striking upon the closing-spring *w*, but it is also held in its attracted position by the magnetization of the core *c*, due to the shunt-current passing through the auxiliary coil *e*, while the contact between the cam and the contact-piece of the distributor takes place. In this case there can only be produced a single induction-spark, because there has only been a single interruption of the primary current.
25. When, instead of only having a single-cylinder motor, a motor with several cylinders is used and it is not desired to distribute the induced current, there are employed for the ignition several coils, (two, three, four, according to the number of the cylinders), which are generally contained in one and the same casing. These coils can either be operated by separated interrupters or by a single interrupter. In the latter case the interrupter is attracted by an electromagnet in which may
- be employed the two windings hereinbefore described.
30. Figs. 5 and 6 show a double coil provided with a single interrupter actuated by a special electromagnet with double winding. The said double coil comprises two induction-coils *a'* and *a''*, arranged horizontally. At the upper part, upon a wooden plate *b*, closing the casing containing the coils, is fixed an electromagnet with two branches *c*, carrying on the one branch a thick-wire winding *d*, Fig. 7, and the shunt-winding *e*. The action of this double coil will be readily understood from the following description of the diagram Fig. 7, which corresponds to a quadruple coil, as the action is exactly the same in both cases. On this diagram the four induction-coils *a' a'' a' a''* are connected in parallel upon the battery-circuit, and *f' f'' f''' f''''* are the screw-posts which connect them to the springs or contact-pieces of the distributor *l' l'' l''' l''''* of the primary current. *g* is the distributing-cam, and *h* is the battery, or source of the primary current. All the thick-wire windings of the coils are connected to the commutator *i* by a single wire *j*, and the tongues *h* and *l* of the commutator are respectively connected with the thick-wire windings *d* and the thin-wire shunt-windings *e* of the electromagnet *c*. The action of this arrangement takes place as follows: When the primary current is sent by the distributor into one of the four coils, the primary current arrives in the electromagnet *c*, which causes the rupture of the circuit. The shunt-winding *e* then keeps the interrupting-tongue attracted, as in the case of a single coil, so long as the cam *g* of the distributor is in contact with the corresponding contact-piece *l*. There is thus obtained a single spark, on the condition, of course, that the commutator *i* is suitably placed.
35. On the modified diagram Fig. 8 instead of the electromagnet *c* having its two windings *d* and *e* placed upon one and the same branch the said windings are each placed upon one of the branches of the electromagnet. As in all induction-coil igniting apparatus, a condenser *m* is arranged in shunt of the terminals of the interrupter, Figs. 7 and 8. A suitable space is reserved for this purpose in the casing of the coils—such as at *y*, for example, in Figs. 1 and 5.
40. Having thus described the nature of this invention and the best means I know of carrying the same into practical effect, I claim—
1. In an induction-coil, the combination with the armature of the interrupter of an electromagnet having two windings serving to operate the armature, the one winding being of thick wire and being adapted to have the main current pass through it, while the other winding is of thin wire and has a shunt of the main current passed through it, substantially as and for the purpose described.

2. In an induction-coil the combination with the armature of the interrupter of a coil of thin wire surrounding the core of the induction-coil and connected in shunt to the primary current, operating so as to keep the armature attracted during the continuance of the distributor's contact, substantially as described.

In witness whereof I have hereunto signed my name in the presence of two subscribing witnesses.

JULES CARPENTIER.
